UNITED STATES PATENT OFFICE.

WILLIAM ALLEN PIPHER, OF JASONVILLE, INDIANA.

DEVICE FOR LIFTING WAGON-BODIES FROM THE RUNNING-GEAR.

SPECIFICATION forming part of Letters Patent No. 356,157, dated January 18, 1887.

Application filed March 9, 1886. Serial No. 194,624. (No model.)

To all whom it may concern:

Be it known that I, WILLIAM A. PIPHER, a citizen of the United States, residing at Jasonville, in the county of Greene and State of Indiana, have invented a new and useful Improvement in Devices for Lifting Wagon-Bodies from the Running-Gears, of which the following is a specification, reference being had to the accompanying drawing.

10 My invention relates to an improvement in devices for lifting the bodies of wagons from the running-gears; and it consists in the peculiar construction and combination of parts that will be more fully set forth hereinafter, and 15 particularly pointed out in the claim.

The accompanying drawing is a perspective view of an apparatus embodying my invention.

20 A represents a pulley suspended from a fixed elevated point—such as the roof of a wagon-shed—and B represents a suitable pulley suspended at a suitable distance from the pulley A. A rope, C, passes over the pulleys A and B, and one end of the said rope is provided with a hook or bar, D, and the other 25 end thereof has a sling, E, adapted to be secured to the bed of the wagon. A ring, F, is attached to the rope C at a suitable point, and a rope, G, which is attached to a suitable removable point—such as the side of the wagon 30 frame or wall—is provided with a hook, H, adapted to engage the ring F.

I represents a chain, having one end attached to the ground or floor by a staple, K, and provided at its opposite end with a hook, L.

35 The wagon is driven under the hoisting apparatus, and the chain I is hooked to one of the standards. The bar or hook D is then passed between and caused to engage with two of the spokes of one of the rear wheels of the 40 wagon, and the sling E, at the other end of the elevating-rope, is attached to the wagon-bed. The wheel is then turned by grasping the spokes near their outer ends, which causes the elevating-rope C to wind upon the inner 45 end of the hub of the wheel, and thus raises the wagon as far as the chain I will permit, and continued rotation of the wheel causes the ele-

vating-rope to raise the body of the wagon from the running-gear thereof, as shown in the accompanying drawing. The hook H is then 50 engaged with the ring F, to support the wagon-body in its elevated position when the bar or hook D is disengaged from the wheel and the elevating-rope released therefrom, and the chain I unhooked from the wagon-standard, 55 when the running-gear may be drawn away divested of the body or bed.

In order to lower the bed to the wagon, the chain I is hooked thereto and the elevating-rope secured to the wheel by the hook or bar 60 D, and the wheel is turned until the elevating-rope tightens, when the hook H is released from the ring F, and the wheel is then turned in the reverse direction, causing the body of the wagon to be lowered in the proper place 65 upon the running-gear, as will be very readily understood.

An apparatus thus constructed is of great utility to farmers and teamsters, as it enables the body of the wagon to be raised from 70 the running-gear or placed thereon with a very small expenditure of labor, and without the risk of injury to the wagon.

Having thus described my invention, I claim—

75 The combination of the hoisting-rope adapted to run over certain pulleys, and connected at one end to the hub of a wagon-wheel, with the detaining-chain or means I attached to the running-gear to prevent it from being raised 80 above a certain point, and the hook or device H, to engage with the hoisting-rope, whereby upon connecting the other end of the hoisting-rope to a wagon-bed and rotating the wheel 85 the rope may be wound around the hub and the wagon-bed raised, substantially as described, for the purpose set forth.

In testimony that I claim the foregoing as my own I have hereto affixed my signature in presence of two witnesses.

WILLIAM ALLEN PIPHER.

Witnesses:

CLARA HICKS,
WINNIE BONHAM.
